United States Patent Office.

FRANCIS ARNOLD, OF HADDAM NECK, CONNECTICUT.

Letters Patent No. 79,430, dated June 30, 1868.

IMPROVED WAGON-JACK.

The Schedule referred to in these Letters Patent and making part of the same.

TO ALL WHOM IT MAY CONCERN:

Be it known that I, FRANCIS ARNOLD, of Haddam Neck, in the county of Middlesex, and in the State of Connecticut, have invented certain new and useful Improvements in Wagon-Jacks; and do hereby declare that the following is a full, clear, and exact description thereof, reference being had to the accompanying drawings, and to the letters of reference marked thereon.

In the annexed drawings, forming part of this specification—

Figure 1 represents a side view of the wagon-jack ready for use,

Figure 2, a bottom view of the tongue, and

Figure 3 a bottom view of the side-holder or collar.

The nature of my invention consists in a collar, which is to be adjusted with a set-screw, or any other suitable device, to an upright post; and in providing it with a movable tongue and lever, to raise the axle of a wagon for any purpose desired.

To enable others skilled in the art to make and use my invention, I will proceed to describe its construction and operation.

In the annexed drawings, A represents the upright post, on to which the side-holder or collar, B, is adjusted in the most convenient manner, so that the machine can be used for any wagon, whether high or low. The side-holder or collar B is made of cast iron, with a hole through it, to fit the post A, as shown in fig. 3, and on its side are two journals, *a a*, with lugs *b b* on one side of them, all cast together in one piece. These journals *a a* are for the purpose of fastening the tongue C and lever D, both of which are made of cast iron, and have holes through them, with slots *c c* on the side of the holes, to fit the journals and their lugs. By this arrangement the tongue and lever can be put on and taken off without the trouble of taking out and inserting pins. The tongue C has on its top or upper side corrugations, to lay the axle in, as shown in fig. 1, and on its bottom side rims *d d*, which form a groove for the lever to work in, so that it will not slip off from the tongue. The rims *d* are shown in fig. 2. The lever D is pivoted on one of the journals *a*, and lifts the tongue C, so that, when it is placed under the wagon, it will raise the axle, and the wheel can be taken off, if desired.

Having thus fully described my invention, what I claim as new, and desire to secure by Letters Patent, is—

1. The adjustable collar B, with hole to fit post A, and provided with journals *a a* and lugs *b b*, arranged substantially as and for the purposes herein set forth.

2. The movable tongue C, with corrugations on its upper side, and the rims *d d* on its lower side, substantially as and for the purposes herein set forth.

3. The combination of the adjustable collar B, movable tongue C, and movable lever D, arranged and operating substantially as and for the purposes herein set forth.

In testimony that I claim the foregoing, I have hereunto set my hand, this 23d day of April, 1868.

FRANCIS ARNOLD.
